United States Patent Office.

JOHN L. KENDALL, OF FOXBOROUGH, MASSACHUSETTS.

Letters Patent No. 89,152, dated April 20, 1869.

IMPROVED GARMENT-SUPPORTER.

The Schedule referred to in these Letters Patent and making part of the same.

To all persons to whom these presents may come:

Be it known that I, JOHN L. KENDALL, of Foxborough, in the county of Norfolk, and State of Massachusetts, have invented a new and useful Coat or Garment-Supporter; and I do hereby declare the same to be fully described in the following specification, and represented in the accompanying drawings, of which—

Figure 1 denotes a front elevation:

Figure 2, a rear view; and

Figure 3, a vertical section of the article on an enlarged scale.

The article consists not only of a metallic ring, but a perforated button or attachment-plate hinged to the ring.

There is also combined with the two a flat annulus or guard-ring, projecting from the hinge and extending back of the perforated disk or button.

By means of the perforated disk, the ring hinged to it may be secured to a coat or other article of apparel by thread sewed through the eyes or holes of the disk.

The flat or guard-ring, by being laid against the surface to which the disk is to be sewed, receives the stitches or thread which are extended through it, and serves to sustain the hinge and prevent its disconnection from the ring, when the article is in use.

In the drawings—

A denotes the ring.

B, the perforated disk.

a a, the holes, perforations, or eyes thereof.

C, the hinge, and

D, the flat or guard-annulus.

The latter I usually make of a diameter somewhat greater than that of the disk B, which, under such circumstances, I make with a diameter a little less than the internal diameter of the ring.

The object of such a construction of the disk and guard, is to enable the latter to so project beyond the

periphery of the disk as to afford a rest or support for the ring when turned down so as to encompass the disk.

The part of the guard so extending beyond the disk serves to prevent the ring, when turned down, from wearing into the cloth or article to which the disk may be affixed.

Figure 4 is a view of the disk, the guard-annulus, and the hinge, as formed from a flat sheet of metal, preparatory to being bent and arranged in manner as shown in the other figures.

The article may consist of the ring and the perforated disk hinged together, but it is preferable to make it with the addition of the flat guard-annulus, as in such case it is rendered stronger and more efficient.

The article in question is designed to take the place of a common loop, as usually affixed to a coat for the purpose of enabling it to be suspended from a hook, or peg, such a loop, as usually made, being composed of a piece of tape or braid, and being liable, when in use, to soon become worn out, or detached from the coat or garment.

I claim the new manufacture of coat or garment-supporter, or metallic ring A, and perforated metal disk B, applied or hinged together as and for the purpose specified.

I claim the combination of the flat guard-annulus D with the perforated disk B, the hinge C, and the ring A, applied together as set forth.

I claim the arrangement of the flat-guard annulus D, so as to project beyond and around the periphery of the perforated disk, in manner and for the purpose set forth, when the disk is hinged or applied to the ring A, as and for the object described.

JOHN L. KENDALL.
